ENGINE ROCKER ARM

James M. Leake, Monroe, Mich.

Application August 3, 1945, Serial No. 608,710

6 Claims. (Cl. 74—519)

1

This invention relates to improvements in engine rocker arms, and more particularly to the type of rocker arm used to operate the valves of an overhead valve internal combustion engine.

My co-pending application, Serial No. 553,645, now Patent No. 2,415,213 issued February 4, 1947, provides a hollow stamped rocker arm in which the oil is forced to the top of the arm member and then flows over the top of the arm member to provide lubrication for the contacting bearings.

My improved engine rocker arm provides a lubrication system which acts more readily when the engine is started. It also provides a lubrication system that is enclosed in the arm member thereby avoiding difficulties encountered by dirt accumulating in the oil passageway.

Difficulty has also been encountered in properly distributing the oil to the ends of the engine rocker arm. Very little lubricant is desired on the tappet end of the intake valve because the vacuum in the intake manifold draws the oil in around the intake valve stem and causes excessive oil consumption. Only a small quantity of oil is desired on the tappet end of the exhaust valve because the excess oil burns on the stem forming a carbon deposit which in turn causes the valves to stick. My improved engine rocker arm is adapted to provide oil to either or both ends of the engine rocker arm and also to control the quantity.

One of the objects of my invention is to provide an engine rocker arm that is light in weight.

Another object of my invention is to provide an engine rocker arm with a hollow cross sectional construction formed from sheet metal.

Another object of my invention is to provide an engine rocker arm that will provide lubricant at either or both ends of the rocker arm.

Another object of my invention is to provide an oil passageway within a hollow engine rocker arm.

Another object of my invention is to provide an engine rocker arm that provides an oil reservoir within the arm member.

Another object of my invention is to provide an engine rocker arm that provides adequate oil control.

Another object of my invention is to provide an engine rocker arm that is strong, durable, dependable and inexpensive.

Another object of my invention is to provide an engine rocker arm that is adapted to quantity production.

With the foregoing and other objects in view

the invention consists of the novel construction, combination and arrangement of parts as herein after more specifically described and illustrated in the accompanying drawing, wherein are shown several embodiments of my invention, but it is to be understood that changes, variations, and modifications can be resorted to which come within the scope of claims hereunto appended.

In the drawing forming a portion of this specification and wherein like numerals of reference designate corresponding parts throughout the several views—

Figure 1 is a front elevation of my novel engine rocker arm.

Figure 2 is a top plan view of my novel engine rocker arm shown in Figure 1.

Figure 3 is an end view of my novel engine rocker arm.

Figure 4 is a sectional view taken along line 4—4 of Figure 2.

Figure 5 is a pictorial view of one of the members of my improved engine rocker arm.

Figure 6 is a sectional view taken along line 6—6 of Figure 4.

Figure 7 is a slight variation of the member shown in Figure 5.

Figure 8 is the front elevation of another form of engine rocker arm embodying my novel invention.

Figure 9 is a top plan view of my novel engine rocker arm shown in Figure 8.

Figure 10 is an end view of the engine rocker arm shown in Figure 8.

Figure 11 is a sectional view taken along line 11—11 of Figure 9.

Figure 12 is a sectional view taken along line 12—12 of Figure 9.

Figure 13 is a fragmentary sectional view showing the upper portion of Figure 11 in an enlarged form.

Figure 14 is a front elevation of the inner member shown in Figure 12.

Figure 15 is a top plan view of the inner member shown in Figure 14.

Referring to Figures 1, 2, 3 and 4, an arm member 10 of inverted U-shaped cross section is stamped from sheet metal. One end of the arm member 10 is provided with a hollow partial prism portion 11 adapted to receive an internally threaded member 12. The opposite end of the arm member 10 is provided with a partial cylindrical portion 13 adapted to receive the stem 14 of the contacting bearing 15. A hub member 16 extends through the side walls 17 of the

arm member 10 intermediate its ends. A bushing or bearing member 18 is secured in the hub 16. An oil passageway 19 extends through the hub 16 and the bushing 18.

A stamped member 20 is provided with a flat wall portion 21 adapted to be secured to the threaded member 12. A lower flat portion 22 extends from the flat portion 21 and is secured to the hub 16. An upper flat portion 23 of the member 20 extends adjacent the upper wall 24 of the arm member 10 and then extends downwardly and is secured to the hub 16. The member 20 engages the side walls 17 as shown in Figure 6.

The stamped member 20 in combination with the side walls 17 and the hub 16 provides a chamber 25 within the arm member 10. An oil passageway 26 communicates the chamber 25 with the under surface of the arm member. The chamber 25 provides an oil passageway as well as an oil reservoir between the oil passageways 19 and 26.

In actual operation the rocker arm is journaled on a rocker arm shaft (not shown). Oil under pressure is fed from a passageway in the rocker arm shaft to the oil passageway 19, through the chamber and passageway 25 and through the oil passage 26 from where it is thrown, by the rocking action of the engine rocker arm, onto the contacting bearing (not shown) which is secured in the threaded member 12.

A small amount of oil collects in the lower portion of the chamber 25. When the engine stops the oil remains in this chamber thus providing a reservoir of oil. When the engine is started the rocking action throws oil out of the oil passageway 26 thereby supplying lubricant to the contacting bearing (not shown) as soon as the engine starts. In the present type of engine rocker arm no reservoir is provided and hence no lubrication is provided until oil reaches the contacting bearing fed under pressure from a supply source by an oil pump. Under these conditions the contacting bearing (not shown) is never lubricated during the starting period.

My novel engine rocker arm overcomes this difficulty. My novel arrangement also provides an internal oil passageway in a hollow engine rocker arm. This prevents dirt from collecting and clogging the oil passageways. My novel arrangement also prevents oil from reaching the fixed contacting bearing 15.

The stamped member 20 is preferably secured in place by a brazing or welding process. The strength of the arm member is also increased by the stamped member 20. The threaded member 12 is secured to the stamped member 20, thus when pressure is applied to the engine rocker arm in operation part of the strain is transmitted by the stamped member 20 to the hub 16 and side walls 17.

Figure 7 shows a stamped member 27 which is similar to the stamped member 20 except that it is provided with side walls 28. When assembled the side walls 28 are secured to the walls 17 of the engine rocker arm 10 and thereby help transmit the strain from the threaded member 12 to the side walls 17 of the engine rocker arm 10.

Figures 8 to 12 disclose another form of my novel engine rocker arm. In this form the arm 30 comprises an upper stamping 31 and a lower stamping 32. The stampings 31 and 32 telescope to provide an arm member 33 with double walls at the upper portion. A threaded member 34 is secured within the one end of the arm member 30. The contacting bearing 34, provided with a

stem 35, is secured at the other end of the arm member 30. A hub member 36 extends transversely to the arm member 30. A bushing 37 is secured in the hub 36 provided with an annular bulged portion 38 which in combination with the bushing 37 provides an annular oil passageway 39 surrounding the bushing 37. An oil passageway 40 communicates the inner surface of the bushing with the annular oil passageway 39.

A stamped inner member 41 is located between the side walls of the lower stamping 32. The wall 42 of the stamping 41 is juxtaposed the threaded member 33 and is preferably secured thereto. The side walls 43 of the inner stamping 41 are secured to the side walls of the lower stamping 32. A bottom 44 is secured to the lower stamping 32. An extending portion extends from the bottom portion 44 to the hub member 36 and then upwardly to meet the upper wall 45 of the upper stamping 31.

The stamped inner member 41 in combination with the side walls and upper walls of the arm member 30 provides a chamber 47. The oil passageway 48 communicates the chamber 47 with the under surface of the arm member 30. In operation oil is fed under pressure from a rocker arm shaft (not shown) to the oil passageway 49 and is then forced through the annular oil passageway 39 into the oil passageway 48. Some of the oil flows out of the top of the oil passageway 48 over the upper wall 46 and down the side walls of the engine rocker arm onto the fixed contacting bearing 34. The remainder of the oil flows through the oil duct 50 into the chamber 47. The chamber 47 provides an oil reservoir and also provides an oil passageway from the oil duct 50 to the oil duct 48. The rocking action throws the oil from the oil duct 48 onto the adjustable contacting bearing 51.

Since the chamber 47 retains a small oil reservoir 52 at the lower portion thereof, a quantity of oil remains in the oil reservoir 52 when the engine stops. When the engine is started again the rocking action of the engine rocker arm 30 throws a small quantity of oil onto the adjustable contacting bearing 51. In this way the adjustable contacting bearing 51 is lubricated as soon as the engine is started. If this oil reservoir is not provided the adjustable contacting bearing is not lubricated until the internal combustion engine (not shown) runs long enough to pump oil from the source of supply (not shown) to the contacting bearing. Considerable wear of the adjustable contacting bearing is due to this factor.

My novel engine rocker arm provides an internal reservoir 52 to overcome this difficulty. It also provides an internal oil passageway from the hub to the adjustable contacting bearing. My novel engine rocker arm also provides a member extending from the threaded member to the hub to help carry and distribute the stresses therebetween.

The upper stamped member 31, the lower stamped member 32, the threaded member 33, the stamped inner member 41, the fixed contacting bearing 34 and the hub 36 are preferably brazed into a substantially one piece member. The bushing 37 is press fitted in the hub 36, although it will be apparent to those skilled in the art that these members may be welded or otherwise secured together.

From the above description it will be apparent that both forms of my invention shown, and described provide a hollow arm member, a

stamped member extending from the threaded member to the hub and thereby providing an oil reservoir within said arm member and an oil passage from the hub to the proximity of the adjustable contacting bearing.

The engine rocker arm of the present invention is rugged in construction and appearance but light in weight. While I have shown and described several embodiments of my invention, it will be apparent to those skilled in the art, that various changes, omissions, additions and substitutions may be made therein without departing from the spirit and scope of my invention, as set forth in the accompanying claims.

What I claim is:

1. An engine rocker arm; comprising an arm member provided with spaced, vertical side walls; a hub member intermediate the ends of said arm member and protruding on each side thereof; and a metal member adjacent said hub member and extending therefrom in contact with said side walls thereby providing a substantially closed chamber between said spaced side walls, an oil passageway extending from said chamber to said hub and an oil passageway extending from said chamber to the lower side of said rocker arm.

2. An engine rocker arm comprising; an arm member, said arm member comprising spaced vertical wall portions and an upper wall portion joining said vertical wall portions; a hub intermediate the ends of said arm member, a contacting bearing secured at one end of said arm member; a threaded member secured between the side walls at the other end of said arm member; and a stamped member secured to said hub, said threaded member, and said arm member to provide a sealed oil passageway from said hub to the proximity of said threaded member.

3. An engine rocker arm comprising; an arm member, said arm member comprising spaced vertical side walls and an upper wall integral with said spaced side walls; a hub intermediate the ends of said arm member; a fixed contacting bearing located at one end of said arm member; a threaded member secured between the side walls of said arm member at the other end thereof; a stamped member secured to said hub, said threaded member and said arm member to provide an oil reservoir; an oil passageway extending from hub to said oil reservoir; and an oil passageway extending from said oil reservoir to the proximity of said threaded member.

4. An engine rocker arm; comprising an arm member provided with spaced side walls and an upper wall joining said side walls; a hub member extending transversely to said side walls intermediate the ends of said arm member; a metal member extending from said hub intermediate said spaced side walls whereby an oil reservoir is provided between said spaced side walls; an oil passageway extending from said oil reservoir to the inner surface of said hub and a second oil passageway extending from said oil reservoir to the outer surface of said engine rocker arm.

5. An engine rocker arm comprising; a hollow sheet metal arm member; a hub intermediate the ends of said arm member; a means coating with said hollow arm member to provide an oil chamber within said hollow sheet metal arm member; an oil passage extending from said oil chamber to the inner surface of said hub and an oil passageway extending from said oil chamber to the outer surface of said hollow sheet metal arm member.

6. An engine rocker arm comprising; an arm member with spaced side walls and an upper wall joining said side walls; a threaded member secured between said spaced side walls; a hub intermediate the ends of said arm member, said hub provided with an annular bulged portion; a tubular bushing in said hub coating with said annular bulged portion to provide an annular oil passageway between said hub and said bushing; an oil passageway connecting said annular oil passageway to the inner surface of said bushing; a stamped member secured to said hub and extending therefrom and coating with said spaced side walls and said upper wall to form an oil reservoir; an oil passageway extending from said annular oil passageway to said oil reservoir and an oil passageway extending from said oil reservoir to the proximity of said threaded member.
